UNITED STATES PATENT OFFICE.

JULIUS O. TUTTLE AND ROY C. TUTTLE, OF SIOUX CITY, IOWA.

DRUMMER'S GAME.

Application filed April 18, 1927. Serial No. 184,534.

Our invention relates to games of the type played with a board and chips and its primary object is to provide an entertainment, imitating the experiences of a traveling salesman.

More particularly our game is embodied in a board having a representation of a map with cities indicated thereon, together with chips for controlling the movement of a 10 player representing a drummer from one city to another.

Another object of our invention is to provide a game wherein the player, impersonating a drummer, travels from one city to another, as indicated by the chip he draws and in so doing is obliged to pay traveling expenses and, when arriving at his destination, receives an order, as indicated by another chip which is drawn by him.

20 A further object is to provide a novel method for computing the expenses of traveling from one city to another in substantially the proper ratio according to the distance, comprising the dividing of the board 25 into squares which serve to measure the distance.

A further object of our invention is to provide a game which combines with the competitive taking of orders in various cities 30 by the player, the possibility for comic situations to arise, as, for instance, where a player finds himself sent to a city entirely out of the way of the country in which the selling campaign is carried out and thereby 35 endures a penalty, or where a player, after making a long trip from one city to another, finds that the object of his trip has moved to a new locality.

With these and other objects in view, our 40 invention consists in the construction, arrangement and combination of the various parts of our device, whereby the objects contemplated are attained, as hereinafter more fully set forth, pointed out in our claims, and illustrated in the accompanying drawings, in which:

Fig. 1 shows the board used in playing our game.

Figs. 2, 3, 4, and 5 show various types of 50 the chips used to control the direction and distance to which a player travels.

Figs. 6, 7, 8 and 9 show various types of the chips which determine the results of the player's sales, if it is after arriving at his 55 destination.

Fig. 10-14 show various types of the

chips which are used as currency for paying expenses.

In Fig. 1 we have shown a game board which may be used in the game of my invention and which embodies an outline map of the United States, as at 10, super-imposed upon a field of squares 11, each of which has sides of approximately 100 miles length in comparison to the distances upon the map. 60 Within the outline map the various States or Territorial divisions are indicated as at 13 and the few exceptionally large cities are indicated with a star as at 14.

The city of New York, indicated at 15, is 70 used as a starting point for the traveling of the drummer. Assuming that four players are engaged in playing the game, each player will be given a quantity of money for expenses in the form of chips, as indicated in 75 Figs. 10-14 inclusive. In order to obtain convenience in assorting the chips, after a game has been finished, into four equal quantities, they are provided in four different colors, as indicated in Figs. 11, 12, 13 and 80 14. Within the group of chips, comprised in each of these colors, there are chips of several different denominations, as indicated in Figs. 10 and 11, showing chips of the same color but differing dimensions. 85

(Each player is provided with two color pins or pegs for making his moves, the set of each player being of a color different from that of all the other players so that there will be no confusion in the making of 90 moves.)

The game is started by each player placing a peg at New York city, where the selling campaign starts. The player will continue to travel as long as his money holds 95 out.

In turn each player draws a chip from a pile of the chips, indicated in Figs. 2-5, respectively, of which there are a considerable number, enough to hold out until the last 100 player has exhausted his expense money. These chips are colored differently from all other chips, as indicated by the color lining and will be hereafter referred to as travel chips. The ordinary travel chips 16, shown 105 in Figs. 2 and 3, are provided with the name of a city, as at 17, and indicate normal trips to towns where ordinary orders can be secured. Assuming a player to have drawn the chip shown in Fig. 2, he will leave his 110 one pin standing at New York city and place his other pin upon the dot indicating

Topeka, Kansas. He will then count the squares intervening between New York city and Topeka, Kansas, proceeding either in a horizontal or vertical direction or in a diagonal direction. Squares can thus be counted from side to side or from corner to corner. In this case, in order to find the shortest route to his destination the player proceeds along the dotted line 18, taking a diagonal route to reach the horizontal row of squares in which the destination is located and then following this row of squares along the line 19. In so doing, he counts the square including the destination but not the square including the starting point, thus finding that the distance of his trip from New York city to Topeka is 1300 miles.

Before he arrives at his destination, the player must pay his railroad fare, which is computed by paying five dollars for each one hundred miles travelled. This amount covers mileage, baggage, Pullman, diners, etc., and is paid from the money chips held by the player to a pile designated as the cashier.

The money chips, held by the cashier, are kept separated as to value, as they will be frequently needed in making change. Any color is good in making change, the different colors being used merely to make it easy to get the game started with equal amounts of money among the players.

The destination having been reached and the mileage paid for, the player then draws a chip from the pile including those shown in Figs. 6-9 inclusive, which chips may be conveniently referred to as order chips. The ordinary order chip 20, shown in Fig. 6, will include a column 21, indicating the number of orders and a column 22, indicating the expense of the stay in the particular town where the order is taken. Before making another move, the player pays for his expenses while in the town.

Some of the order chips are provided with a star, as at 23, and these starred chips will be referred to by the reference character 24. The difference between the starred chips 24 and the ordinary chips 20 lies partly in the size of the order and partly in the fact that should a player draw a starred chip while he is located at a starred city, both the traveling chips and order chips count double as to cities, number of orders and score, (later referred to), but do not double the expense. These double starred draws are honors and should be kept apart from the other chips for convenience when counting up the final scores.

The traveling expenses include a few chips 25, which are starred, as at 26, and which carry the player to such cities as San Francisco, Chicago and other large centers which are starred on the map as already pointed out. In addition to the function of

these starred chips, when drawn just previously to a starred order chip, as just described, the starred traveling chips entitle the player to draw an extra order chip if the chip just drawn carries a three-score, 70 two extra order chips if the chip just drawn carries a five-score and three extra order chips if the chip just drawn carries a ten-score.

The score numbers just referred to and previously referred to in connection with the order chips are located at 27 on the travel chips and at 28 on the order chips. It will be noted that on the ordinary travel chip and the ordinary order chip 20, the 80 score numbers are low as compared with the score numbers on the starred travel chips 25 and starred order chips 24. The score numbers are not all the same, however, on the ordinary travel chips or order chips, as is 85 shown in Figs. 2 and 3 in the case of the travel chips.

In addition to the functions already described to the score numbers, these scores are counted in computing the final score of 90 a player after his expense money has given out. The score is counted in three sections, as follows:

- (1) A total score on travel chips.
- (2) A total number of orders on order 95 slips.
- (3) A total score on order chips.

These amounts are added together to obtain the player's total and the player obtaining the highest total wins the game.

In order to add enjoyment to the game, some of the order chips are provided with such notes as, (customer burned out), (sore on the house), (left town), etc. When a player draws a chip of this type, indicated 105 in Fig. 9 at 29, he loses a turn but has to pay expenses for staying in the town just the same.

A similar element of form is introduced when a player draws a chip such as shown 110 at 30 in Fig. 5, which sends him on a wild goose chase to a city in a foreign country, causing him to incur a penalty to the house of \$50.00, paid the same as the paying of expenses giving him a low score but entitling 115 him, however, to the usual opportunity of obtaining an order by drawing an order chip.

There are two cancellation chips among the order chips referring to two orders, numbered on the chip as shown in Fig. 8 at 31, which orders have been cancelled. These orders must be discarded by the player at the end of the game, providing that the chips calling for the cancellation have been 125 drawn by any player.

The play proceeds by each player moving the pegs each time to show the town just left and the destination. It will now be seen that in my game the experiences of a

traveling salesman are imitated as closely as possible. If a player can make short jumps, he will gain a higher final score because his expense money will last longer. In the same manner, a traveling salesman finds it good business to make as short jumps as possible. If a player can be sent to a big city, he stands a better chance of obtaining a high score because the score values for the big cities are increased. However, the mere fact that a player goes to a big city does not guarantee a big order. His order depends entirely upon his initiative, while in the city, and this is indicated by the drawing of an order chip.

The expense of the player is directly proportional to the distance he travels and this is computed with fairly substantial accuracy by the square method.

The game is educational in that it teaches the location of important commercial centers and comparative sizes and the distances between them.

Some changes may be made in the construction and arrangement of the parts of our invention without departing from the real spirit and purpose of our invention, and it is our intention to cover by our claims, any modified forms of structure or use of mechanical equivalents, which may be reasonably included within their scope.

We claim as our invention:

1. In a game, a board comprising a representation of the map, cities indicated upon said map, a few of said cities being distinguished from the others by distinguishing marks, and travel chips for directing a player from one city to another, a few of said travel chips having corresponding distinguished characters and when drawn while the player is at one of the cities having such distinguishing connections serving to double the score which would otherwise be had by the player on that play.

2. In a game, a board comprising a representation of a map, cities indicated upon said map and a plurality of order chips to be drawn by the player upon arriving at a particular city, the bulk of said chips indicating orders and a few of said chips indicating no orders, the reason for said no order being indicated upon such no order chips.

3. In a game, a board comprising a repre-

sentation of a map, cities indicated upon said map and a plurality of travel chips for directing a player to a city, a few of the travel chips containing destinations foreign to the country comprising the main portion of the map and carrying a penalty.

4. In a game, a board representing a map, cities indicated upon said map, squared, Territorial divisions super-imposed upon said map, travel chips indicating the destination of a player and money chips to be used in paying the expense of traveling to said destination over a distance computed by means of said squares.

5. In game, a board representing a map, cities indicated upon said map, travel chips indicating the destination of the player and money chips used in paying the expense of traveling to said destination.

6. In a game, a board representing a map, cities indicated upon said map, squared, Territorial divisions super-imposed upon said map, travel chips indicating the destination of the player, order chips indicating the number of orders taken at said destination and indicating the expense while staying at said destination and money chips used in paying the expense of arriving at said destination computed by means of said squares and in paying the expense while staying at said destination.

7. In a game, a board representing a map, cities indicated upon said map, travel chips indicating the destination of the player and money chips used in paying the expense of traveling to said destination, and order chips to be drawn by the player upon arriving at a particular city.

8. In a game, a board representing a map, cities indicated upon said map, travel chips indicating the destination of the player and money chips used in paying the expense of traveling to said destination, and order chips to be drawn by the player upon arriving at a particular city, the bulk of said chips indicating orders and the few of said chips indicating "no order", the reason for said "no orders" being indicated upon such "no order" chips.

Signed this 15 day of April, 1927, in the county of Woodbury and State of Iowa.
